HYDRAULIC STAGE METER

Marjen H. Collet, Fort Collins, Colo.

Application August 6, 1940, Serial No. 351,635

3 Claims. (Cl. 73—319)

(Granted under the act of March 3, 1883, as amended April 30, 1928; 370 O. G. 757)

This application is made under the act of March 3, 1883, as amended by the act of April 30, 1928, and the invention herein described and claimed, if patented, may be manufactured and used by or for the Government of the United States of America for governmental purposes without the payment to me of any royalty thereon.

I hereby dedicate the invention herein described to the free use of the people in the territory of the United States to take effect on the granting of a patent to me.

This invention relates to water gages and is more particularly concerned with a device for measuring static hydraulic heads.

An object of this invention is the provision of such a device which can indicate instantaneous stages of a body of water and, also, the maximum stage over a given period of time, in either placid or moving water.

A preferred embodiment of my invention is illustrated in the accompanying drawing, in which Figure 1 is a front elevational view, Figure 2 a side elevational view without the metal guard, and Figure 3 an exploded view of the assembly at the lower end of the tube 12. Figure 4 is a side view of the float and friction skirt assembly.

Referring with more particularity to the drawing, in which like numerals designate like parts, the device illustrated comprises a suitable mounting board 10 which may be of any suitable material, such as water-resistant lumber, non-corrosive metal, and so forth. This mounting board is also preferably streamlined from one edge to the other, so that when the instrument is used in moving water, false stages will not be created by turbulence about the instrument. On the front face of the instrument a longitudinal groove 11 is disposed to receive a piezometer tube 12. This tube is open at its lower end 13. The upper end of this tube is bent outwardly at right angles and drawn to a small orifice 14. To the lower end 13 of the tube 12, there is connected another tube 15, preferably of metal. The upper end of this tube 15 is connected to the end 13 of the piezometer tube by means of a water-proof coupling of any suitable type, such as a removable rubber collar 16. Between the tubes 12 and 15 there is disposed a wall 17 having an aperture 18 therethrough, the area of which is substantially less than the cross sectional area of the tube 12. The lower end of the tube 15 is provided with a bell-mouthed orifice 19, which is turned in a vertical plane and set flush with the

face of the mounting board 10, substantially as shown.

Within the tube 12 there is disposed the float and friction skirt assembly illustrated in Figure 4, consisting of a float 20 which may be made of any suitable material, such as thin blown glass, or light waterproof plastic, or any other highly buoyant material. To the foot of the float 20 there is secured a friction skirt 21, the function 10 of which is normally to prevent the float 20 from descending while permitting it to rise in the tube 12 when buoyed upward. By these means the maximum stage of a body of water under observation can be determined for any given period 15 of time. The skirt 21 is preferably composed of soft rubber, the projecting arms 22 being flared, substantially as illustrated. The arms 22, as 20 illustrated, are fashioned similar to the arms of a Maltese cross. However, any other suitable shape may be employed.

Under certain circumstances it may be desirable to employ a foot 23 at the bottom of the mounting board 10 to steady the instrument in shallow bodies of water, such as along the banks 25 of rivers, where the foot 23 can be driven into the ground near a tree or post and held in position. Adjacent to the tube 12 there is disposed a scale 24 which may be calibrated in any suitable units for measuring the level of water stages.

30 To use the instrument, the float with the friction skirt is forced to the bottom of the tube to rest on the diaphragm 17. This may be accomplished by blowing into the aperture 14. The instrument is then set in a body of water. If the 35 water is in motion the instrument should be set so as to take advantage of the streamlining of the mounting board 10 which normally would require the face of the device to be parallel to the direction of motion of the water. Water is admitted 40 to the tube 12 through the orifice 19 and as the water rises in the tube 12, it carries the float 20 with it. This float is provided with a water line mark 25 which is used as a line of reference with respect to the scale 24. Should the static head of 45 the body of water decrease, the float will remain at the highest point reached due to the friction between the skirt 21 and the inner walls of the tube 12. At the same time, the elevation of the water line below the float 20 will indicate the 50 stages of the body of water at any particular time. By these means, therefore, the maximum stage reached by the body of water over any given period of time is indicated by the float 20.

The wall 17 not only prevents the float 20 from 55 falling out of the tube 12, but also prevents sur-

ing of the column of liquid in the tube 12. The removable rubber collar coupling 16 permits replacement of the float or skirt or the making of any necessary repairs thereof with ease.

If desired, a metal guard 26, shown, in Figure 1 only, may be placed around the tube 12 to prevent debris from injuring it.

Although, in the above description of my invention, particular reference was made to the measurement of bodies of water, it is to be understood that bodies of other fluids may be measured in a similar manner.

Having thus described my invention, I claim:

1. A fluid stage indicator, comprising a vertical transparent tube, means for mounting said tube, including a streamlined mounting board, means having a bell-shaped orifice disposed flush with the face of said board and connected to the bottom of said tube, said tube having an aperture near the top thereof, a water float disposed in said tube, means associated with said float to engage frictionally the inner walls of said tube normally to prevent the float from descending, while permitting it to rise in the tube, and means, including a scale adjacent said tube, for determining different elevations of said float and of a column of liquid in said tube.

2. A fluid stage indicator, comprising a vertical transparent tube, means for mounting said tube,

including a streamlined mounting board, means having an orifice disposed flush with the face of said board and connected to the bottom of said tube, said tube having an aperture near the top thereof, a float disposed in said tube, means associated with said float to engage frictionally the inner walls of said tube normally to prevent the float from descending, while permitting it to rise in the tube, means, including a scale adjacent said tube, for determining different elevations of said float and of a column of liquid in said tube, and a perforated wall between said orifice and said tube.

3. A fluid stage indicator, comprising a vertical transparent tube, means for mounting said tube, including a mounting board, means having an orifice disposed flush with the face of said board and connected to the bottom of said tube, said tube having an aperture near the top thereof, a float disposed in said tube, means associated with said float to engage frictionally the inner walls of said tube normally to prevent the float from descending, while permitting it to rise in the tube, means including a scale associated with said tube for determining different elevations of said float and of a column of liquid in said tube, and a perforated wall removably disposed between said orifice and said tube.

MARJEN H. COLLET.
